UNITED STATES PATENT OFFICE.

CHARLES R. STEVENSON, OF MISHAWAKA, INDIANA, ASSIGNOR TO NATIONAL VENEER PRODUCTS COMPANY, OF MISHAWAKA, INDIANA, A CORPORATION OF INDIANA.

HANGER-SUPPORT FOR TRUNKS.

1,282,972.

Specification of Letters Patent. Patented Oct. 29, 1918.

Application filed April 24, 1915. Serial No. 23,708.

To all whom it may concern:

Be it known that I, CHARLES R. STEVENSON, a citizen of the United States, residing at Mishawaka, in the county of St. Joseph and State of Indiana, have invented certain new and useful Improvements in Hanger-Supports for Trunks, of which the following is a specification.

My invention relates to improvements in trunks and it more especially comprises the features pointed out in the annexed claims. The purpose of my invention is to provide a self-contained garment hanger support which is light, compact, economical to make; that largely uses standard metal parts; that, whether used singly or in pairs is free from all accessories; that will positively without sliding the hangers bring out the entire lot at one pull; that combines the hanger plate with an internally sliding track extension; and that maintains the alinement of the pull out feature to the hangers without complex means.

With these and other ends in view I illustrate in the accompanying drawing such instances of adaptation as will disclose the broad features without limiting myself to the specific details shown.

Figure 1 is a side elevation of a track, an extension and the supplementary hanger plate connected therewith, partly in section.

Fig. 2 is an enlarged transverse section of the parts supported by a side bracket formed as a sheet metal stamping.

Fig. 3 is a view similar to Fig. 2 substituting a solid extension rod for the tube of Fig. 2.

Fig. 4 is a diagrammatic front elevation of a pair of supports placed in a trunk and connected with a transverse bar.

While I instance the adaptation of my improvement to use on the sides of a trunk, it is quite obvious that, if desired I may attach the same to the under side of the trunk top.

A stamped support ordinarily made right and left hand has a fastening portion, 3, an offset part, 4, a support, 5, and a "roll," 6. Within the roll a tubular extension, 8, may be placed. The front end thereof may have a suitable plug, 16, suitably held therein. The tube, 8, abuts the enlarged diameter 17, which serves as a seat for the supplemental hanger plate, 12. This abuts 55 against flange, 18. A suitable knob, 19,

may have its stem, 21, riveted into the plug, 16, and it may also hold a connecting bar, 20, in place. The plate, 12, may be of segmental cross section so as to form a round surface on which the hangers rest 60 and at the same time provide greater stiffness. If desired the plate, 12, may rest directly on the roll, 6, in which case the guiding "ring", 14, would be secured on the top of the plate. The rear end of this plate 65 is bent up at 13, to form a pull out projection in front of which hangers, 15, are placed.

The movement of the plate, 12, is simultaneous to that of the tube, 8, and both are 70 limited by the depending end, 15^a, of 14, engaging a pressed up or otherwise formed stop, 11. If desired, 12, may be secured to 17, by means of screws.

If desired I may use a solid extension 75 rod, 7, as instanced in Fig. 3, instead of the tubes, 8, shown in Fig. 2, in which case the knob, 19, may be screwed or otherwise fastened to 17, and any small distance piece placed between 12, and rod 7, at the front 80 end where they are fastened to each other which will sufficiently raise, 12, to accommodate, 6, therebetween. When a solid rod, 7, is used, the roll, 6, may have a slot, 9, into which a pin, 10, may project, the same engaging stop 11, and performing the same function as end, 15^a, of "ring", 14.

It is immaterial as to the kind of side or other support that is used whether stamped, rolled, cast, etc. It will be seen that my 90 device is simple and positive in action with little likelihood of any portions becoming displaced or in-operative under the ordinary service conditions to which articles of this kind are subjected.

What I claim is:

1. In a trunk, a hollow one-piece track having a slot formed lengthwise thereof, a slidable extension within the track, a slotted member slidable outside of 100 the track, a limit stop near the forward end of the track adapted to define the extreme forward movement of the slidable extension, a knob secured to the forward end of the slidable extension, a supplementary slide 105 forming a garment hanger support attached to the slotted member and the knob, and a projection therefrom at its rear end adapted to move all garment hangers that may be found on the slide forward into an accessible 110

- position as the knob and its attached parts is pulled forward.
2. In a trunk, a suitable support having a roll formed track integral therewith, an extension member of approximately the same length as the track placed inside thereof, a knob secured to the forward end of the extension, a slotted sleeve placed on the outside of the track at the rear end thereof, a garment hanger slide partly encircling the track and attached to the sleeve and knob, and means for limiting the movement of the interconnected slideable parts.
3. In a trunk, a combined one-piece support and track, having a slot formed lengthwise thereof on the under side of the track portion, a stop projection extending into the slot near its forward end, a track extension comprising internal and external parts, means for securing the said parts to each other at the front end, a split ring slideable on the outside of the track secured to the external part at the rear end thereof and adapted to engage the stop aforesaid to prevent the extreme accidental withdrawal of the track extension, and an upwardly extending projection at the rear end of the external part adapted to engage any garment hangers that may be found in front of the same.
4. In a trunk, a supporting member also constituting a hollow track having a continuous slot formed therein, a stop extend-

ing into the slot at the forward end thereof, an extension member comprising an inside part and an outside part the latter being placed adjacent the upper wall of the track, means for securing them to each other at the front end, a slotted guide one end of which extends into the range of the track slot, means for securing the guide and the outside part of the extension at the rear end thereof to each other, and a vertical projection formed above the guide the same being adapted to engage garment hangers placed on the outside part in front said projection.

5. In a trunk, a hollow slotted guiding track, a stop at the front end thereof, a garment hanger carrying member slideable adjacent the upper side of the track, a supporting member attached at its front end to said carrying member and slideable within the track, both constituting a track extension, a rear guide secured to the carrying member and slideable on the outside of the track, projections therefrom, one of which is adapted independently to engage garment hangers formed on the carrying member and the other to engage the stop aforesaid.

In testimony whereof I affix my signature in presence of two witnesses.

CHARLES R. STEVENSON.
